FOOT MASSAGER

Martin J. Svoren, Racine, Wis., assignor to Allover Mfg. Co., Racine, Wis., a corporation

Application October 26, 1954, Serial No. 464,712

6 Claims. (Cl. 128—41)

This invention relates to machines for the treatment of the feet and more particularly to an electrically operated vibrator controlled by the user for massaging the foot, or selected parts thereof, for increasing blood circulation, for the relief of tired muscles, etc.

One of the primary objects of my invention is to provide a foot massager embodying a casing shaped to form a foot rest for the user with a novel shaped pad or massage head projecting slightly above the casing, and rapidly vibrated from an electromagnet housed within the casing, the pad being curved transversely and extending across the casing, whereby the foot can be easily and gently slid over the pad to obtain the desired massaging action therefrom.

Another salient object of my invention is the provision of novel means located in close proximity to the pad for opening and closing the circuit through the electromagnet, whereby the operation of the machine can be conveniently controlled by the mere pressure of the foot being treated.

A further important object of my invention is the provision of a novel arrangement of massage plate or pad and switch handle so that these parts will be so co-related that the machine can be instantly stopped or started by pressure from the part of the foot being treated on the switch handle.

A further important object of my invention is the provision of novel means for operatively connecting the switch handle with a quick acting snap switch whereby a minimum amount of pressure is required from the operator's foot to start and stop the motor.

A further object of my invention is to provide a foot massager which will be of a compact and durable construction, and one which will present a pleasing and attractive appearance to the trade.

With these and other objects in view, the invention consists in the novel construction, arrangement and formation of parts, as will be hereinafter more specifically described and claimed, and illustrated in the accompanying drawings, in which drawings:

Figure 1 is a perspective view of the improved massager;

Figure 2 is a longitudinal sectional view through the massager taken on the line 2—2 of Figure 1, looking in the direction of the arrows, illustrating the connection of the massage pad or plate with the vibrator and the relation of the switch handle relative thereto;

Figure 3 is a transverse sectional view through the massager taken on the line 3—3 of Figure 2, looking in the direction of the arrows and illustrating the novel means employed for actuating the snap switch from the switch handle or knob, and

Figure 4 is a fragmentary detail sectional view taken on the line 4—4 of Figure 3, looking in the direction of the arrows, illustrating the means for actuating the snap switch.

Referring to the drawings in detail, wherein similar reference characters designate corresponding parts throughout the several views, the letter M generally indicates the

2

improved foot massager and the same includes a base plate 5 having secured to the upper face thereof a casing 6 for housing the operative parts of the device. The lower face of the base plate 5 preferably carries feet 7 of the suction cup type, whereby creeping of the machine on a floor surface or the like will be prevented. The casing itself can be formed from any desired type of material, such as metal or plastic, and the casing includes front and rear walls 8 and 9, like side walls 10 and a top wall 11. The top wall 11 adjacent to its rear end is provided with an opening 12 through which protrudes the massage pad, head or plate 13 and the switch handle or knob 14.

The massage pad or plate 13 extends transversely across the casing, and is itself curved transversely so as to present an arcuate smooth contour for engaging the sole of a person's foot. To add to the appearance of the device and to give a smooth streamlined contour to the casing, a top polished plate 15 can be secured to the top wall 11 of the casing and this plate is provided with an opening 16 substantially the same shape as the massage plate or pad 13. The front edge of the massage plate 13 is notched, as at 17 for receiving the switch knob 14 and this knob is in the nature of a flat elongated plate formed from rubber or the like. The upper exposed edge of this switch knob is also rounded so as to permit the easy travel of a person's foot thereover without discomfort.

In order to rapidly vibrate the massage pad or plate 13, I provide an alternating electromagnet 18, and the frame 19 of this magnet is secured to a bracket plate 20, which is in turn fastened to the base plate 5 by means of screws 21 and separator sleeves 22 on the screws. A relatively heavy leaf spring 23 of a U-shape is secured to the frame of the electromagnet at one end and the upper arm 24 of this spring has riveted or otherwise fastened thereto the armature 25 for the magnet. The spring 23 normally functions to hold the armature away from the electromagnet and upon the energizing of the magnet the armature will be attracted thereby in the usual manner. Rigidly fastened to the armature 25 adjacent to its upright outer end is an internally threaded boss 26 and this boss protrudes through the opening 12 of the casing. Threaded into the boss is a depending stem 27 formed on or carried by the central portion of the massage pad or plate 13.

In order to open and close an electric circuit through the electromagnet 18, I employ a quick acting snap switch 28 of a type now found in the open market and this switch includes upper and lower leaves 29 and 30 and an intermediate resilient leaf 31. The inner ends of the leaves are held and insulated one from the other by means of blocks of insulation 32 and the lowermost block is rigidly secured to the base plate 5 in any desired manner. The lower leaf 30 merely constitutes a stop for the intermediate resilient leaf 31 and the upper leaf 29 and the intermediate leaf carry contact points for bringing about the closing of a circuit, as will be later brought out. Extending into the casing 5 is an electric cord 33 and the electric wires of this cord are electrically connected to a suitable source of electrical energy. Incorporated in the circuit for the electromagnet 18 is an intensifier or modifier 34, preferably of the type shown in the Wahl Patent No. 2,054,590 issued September 15, 1936. One wire 35 of the electric cord 33 extends to one terminal of the intensifier 34 and the other terminal of the intensifier has connected thereto an electric conductor wire 36 which is in turn electrically connected with the upper leaf 29 of the snap switch 28. An intermediate leaf 31 of the switch has electrically connected therewith a wire 37 which leads to one terminal of the electromagnet 18 and the other terminal of the electromagnet has electrically connected thereto the return wire 38 of the electric cord.

As best shown in Figure 4 the intermediate leaf 31 extends a material distance beyond the upper and lower

leaves 29 and 30 of the switch and this end is provided with an operating head 39.

The novel means employed for actuating the leaf 31 from the knob 14 includes a substantially inverted U-shaped resilient strip 40. The strip includes depending guide legs 41 and 42 connected by a top bight portion 43. Movement of the resilient strip is guided by upright posts 44 and 45. The leg 41 of the resilient strip, has formed on its lower end a right angularly extending foot 46 which is secured to the base plate 5. The tension of the resilient strip 40 is such that the leg 42 and the connecting bight portion 43 are normally held in a raised position and the connecting portion 43 adjacent to the leg 41 is provided with an opening 47 through which the post 44 extends. The connecting bight portion adjacent to the leg 42 is provided with an opening 48 through which can slidably extend the guide post 45 and the lower end of the leg 42 is provided with an apertured foot 49 which slides on the lower end of the post 45. Rigidly fastened to the bight portion 43 is the switch handle or knob 14 and consequently, this knob or handle is normally projected upwardly slightly above the massage plate by the spring strip 40. Upon downward pressure on the handle or knob 14 the spring strip will be flexed downwardly and the leg 42 will slide on the post 45. Rigidly fastened by a screw 50 or the like is a right angularly extending arm 51 and this arm carries a depending operating post 52 in vertical alignment with the knob 39 on the resilient leaf 31 of the switch. The arm 51 is located adjacent to the leg 42 and is carried by the spring or resilient strip at the point of its greatest movement.

When downward pressure is exerted on the switch handle or knob 14, the post 52 will be depressed actuating the leaf 31 and snap the same in a quick action in electric contact with the strip 29 bringing about the closing of the circuit through the alternating electromagnet 18. Upon release of pressure on the handle or knob 14, the same will assume its normal raised position carrying the post 42 up so that the intermediate leaf will again flex and snap away from the leaf 29 into contact with the stop leaf 30.

Changes in details may be made without departing from the spirit or the scope of this invention but what I claim as new is:

1. A foot massaging device comprising a casing having a top wall provided with a transversely extending opening and a foot rest in front of said opening, an alternating electromagnet housed within said casing, an armature for the electromagnet disposed directly below said opening, a foot massaging element carried by the armature and pro-

jecting through said opening, an electric switch for opening and closing a circuit through the magnet, means for operating the switch including a flat plate like knob projecting through said opening and said foot massaging element having a notch in its forward end receiving said knob, the knob normally projecting a slight distance above said foot massaging element and in the path of a foot placed upon said element.

2. A foot massaging device as defined in claim 1, the upper exposed edge of said knob being curved transversely.

3. A foot massaging device as defined in claim 1, and said foot massaging element including a plate extending transversely of the top wall and being curved transversely on an arc of a circle, the notch in said element being in the front edge of the plate.

4. A foot massaging device comprising a casing having a top wall provided with a transversely extending opening, an alternating electromagnet housed within said casing, an armature for said magnet disposed directly below said opening, an internally threaded boss secured to the armature, a massage plate having a stem threaded into said boss and said plate being disposed in said opening and partially projecting through said opening, said plate having a notch in its front edge, a snap switch in said casing for opening and closing a circuit through the electromagnet, means for actuating the snap switch including a knob disposed within said notch and normally projecting slightly above the upper face of the plate.

5. A foot massaging device comprising a casing having a top wall provided with an opening, an alternating magnet housed within said casing, an armature for said magnet, a massage element carried by the armature and projecting through said opening, a snap switch for opening and closing a circuit through the magnet including a contact leaf, means for actuating the leaf including an inverted U-shaped resilient strip having one end anchored in the casing and the other end free, guide posts secured to the casing and arranged therein upon which the strip is mounted, a depending operating post carried by the strip adapted to depress the leaf upon downward movement of the strip, and an operating knob for the strip projecting through said opening.

6. A foot massaging device as defined in claim 5 and said massage element having a notch for slidably receiving the knob.
